(57) **CLAIM**

The ornamental design for a sprayer assembly, as shown and described.

DESCRIPTION

FIG. 1 is a front perspective view of the sprayer assembly, showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front perspective view of the sprayer assembly of FIG. 1 according to a second embodiment, including a red-color periphery indicated by vertical lines, showing my new design;

FIG. 10 is a rear perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

Portions of the sprayer assembly are shown in broken lines. Portions of the sprayer assembly shown in broken lines forms no part of the claimed design.

1 Claim, 16 Drawing Sheets
